UNITED STATES PATENT OFFICE.

EDWARD THORNTON AND GEORGE S. SMITH, OF COITSVILLE, OHIO.

SMOKE-CONSUMING FURNACE.

SPECIFICATION forming part of Letters Patent No. 657,324, dated September 4, 1900.

Application filed March 14, 1900. Serial No. 8,600. (No model.)

To all whom it may concern:

Be it known that we, EDWARD THORNTON and GEORGE S. SMITH, citizens of the United States of America, residing at Coitsville, in the county of Mahoning and State of Ohio, have invented certain new and useful Improvements in Smoke-Consuming Furnaces, of which the following is a specification, reference being had therein to the accompanying drawings.

This invention relates to certain new and useful improvements in smoke-consuming furnaces, and a furnace constructed in accordance with our invention is particularly adapted to consume all the combustibles contained in the fuel, thereby increasing the temperature of heat and obtaining a considerable saving in the consumption of fuel.

One object of our invention is to construct a furnace of this character with means to supply air and steam to the fire-box from beneath the grate-bars, causing the fire to burn more evenly and increasing the temperature of the same without an additional charge of fuel for obtaining this purpose, or, in other words, thoroughly consuming all the combustibles contained in the fuel, thereby obtaining this increased temperature of generating steam more rapidly at a considerable saving in the consumption of fuel.

A further object of the invention is to provide the bridge-wall of the furnace with a series of steam and air ejectors for projecting air and steam against the flame as it crosses the bridge-wall of the furnace, thereby arresting the smoke and combustibles as the same are drawn toward the fuel and causing the consumption of the same, furthermore, arranging at the top of the bridge-wall in alignment with the steam and air ejectors a separate steam and air ejector, through which the air is projected and meets the air and steam as they leave the ejectors of the bridge-wall, this assisting materially in the consuming of the fuel and combustibles as the same are drawn toward the fuel, furthermore forcing the same to a great extent back upon the fire, which also assists in the consumption of the combustibles contained in the fuel.

A further object of our invention is to construct a furnace of this character which will

be extremely simple in construction, strong, durable, efficient in its operation, and comparatively inexpensive to manufacture. 55

With the above and other objects in view the invention finally consists in the novel construction, combination, and arrangement of parts to be hereinafter more fully described, and specifically pointed out in the claim. 60

In describing the invention in detail reference is had to the accompanying drawings, forming a part of this specification, and wherein like numerals of reference indicate corresponding parts throughout the several 65 views, in which—

Figure 1 is a side view, partly in section, of a furnace equipped with our improved device. Fig. 2 is a cross-sectional view, partly in section, taken on the line 1 1 of 7c Fig. 1.

Referring to the drawings by reference-numerals, 1 indicates the side walls of a furnace, 2 the rear walls, and 3 the front walls.

The reference-numeral 5 indicates the door 75 to the fire-box, and 6 the door to the ash-pit.

The furnace is provided with a series of suitable grate-bars 7, a bridge-wall 8, and a boiler 9, secured therein in any desirable manner. 80

Arranged within the bridge-wall 8 is a series of vertical steam and air ejectors 10, connected to a supply-pipe 11, which in turn is connected by means of a union 12 to a steam-feed pipe 13 and air-supply 14. The union 12 85 and its connections are provided with a suitable cut-off 15. The vertical steam and air ejectors terminate at the top of the bridge-wall, as shown, and arranged above the same and extending transversely across the furnace is an air-pipe 16, connected to a suitable source of air-supply (not shown) and which is provided with a series of perforations 17 to permit of the projecting of air therefrom against the steam and air as they leave the 90 vertical ejectors 10.

Arranged beneath the grate-bars of the furnace is a steam and air pipe 18, connected by a union 19 to the air-pipe 14 and steam-supply pipe 13, the union 19 and its connections 100 being provided with a cut-off 20. The air and steam pipe 18 has arranged therein a series of perforations 21 to permit of the projecting therefrom of the steam and air up

through the grate-bars and through the fire, this materially causing the fire to burn more evenly and increasing the temperature of the same without an additional charge of fuel 5 for obtaining such purpose.

The operation of the device is as follows: Assuming that the fire is arranged upon the grate, the smoke, combustibles, and flame as they are drawn toward the flue are arrested 10 by means of the steam and air from the vertical ejectors 11 and the air from the air-pipe 17, this creating a means for forcing the combustibles back upon the fire as well as consuming the same.

It is thought that the many advantages of our improved construction as to the consumption of combustibles contained in fuel, thereby obtaining a considerable saving of fuel, can 15 be readily understood from the appliances used in connection with a furnace, as set forth in the foregoing description and illustrated in the accompanying drawings, and it will be noted that various changes may be made in the details of construction without departing 20 from the general spirit of our invention.

Having thus fully described our invention, what we claim as new, and desire to secure by Letters Patent, is—

The combination with the bridge-wall and combustion-chamber of a furnace, of a perforated pipe 18 extending across the ash-pit beneath the grate-bars for feeding steam to said combustion-chamber, a pipe 11 extending through the bridge-wall with a series of ejectors connected thereto with their outlets 30 at the top of the bridge-wall, said pipe 11 and the pipe 18 connected to a common steam-supply, an air-supply for said pipes 11 and 35 18, and a perforated pipe 16 located above the bridge-wall for supplying cold air to the steam and hot air emitted from the injectors in the bridge-wall, as and for the purpose described.

In testimony whereof we affix our signatures in the presence of two witnesses.

EDWARD THORNTON.
GEORGE S. SMITH.
